COMBINATION AIR WASHER AND
HUMIDIFIER

Philip I. Holmes, Brighton, Mass.

Application January 20, 1942, Serial No. 427,405

1 Claim. (Cl. 261—121)

This invention relates to dust removal means for use with vacuum cleaners or other devices that remove dust from articles such as rugs.

In the typical vacuum cleaner, the dirt is sucked from the rug or other article that is being cleaned by means of a blower and is then passed into a dirt collector where the dirt particles are trapped by one means or another, with the carrying air thereafter being permitted to pass on back into the room.

It is well known that the filters or other traps that may be used are not capable of removing all of the dirt and dust particles from the carrying air, although the major portion of the dirt is caught. It is with respect to the removal of the remaining small particles of dirt and dust that are not caught by the first collector that this invention is particularly concerned. This invention provides means, in the form of a unit which may be attached to vacuum cleaners, through which the air under substantial pressure coming from a prior dust collector may be passed. The construction is such that the dust particles contained in the air passing through the unit will be filtered out so that the air leaving the unit will be substantially free of dust.

A further object of the invention is to provide means which will humidify the air that passes through the unit so that the humidity of the room in which the vacuum cleaner is used will be raised.

A further object of the invention is the provision of visual means within the dust removing unit for indicating that the unit is functioning properly.

These and other objects of the invention will become more apparent as the description proceeds with the aid of the accompanying drawing, in which:

Fig. 1 is a side elevation of the complete unit, showing it positioned on the end of an elbow leading from the prior dust removing source;

Fig. 2 is a cross-sectional elevation of the unit shown in Fig. 1;

Fig. 3 is a section on the line 3—3 of Fig. 2;

Fig. 4 is a sectional elevation similar to that shown in Fig. 2 and disclosing a modified form;

Fig. 5 is a sectional elevation, broken away in part, showing a further modification.

Referring to Figs. 1 and 2, the unit comprises a cup-shaped casing 2 having a cylindrical wall 4 and a bottom 6. Extending upwardly through the center of the bottom is a tube 8. The extension 10 of the tube below the bottom may be of any convenient length and formation to

provide means for connection to a pipe, such as pipe 12, shown in Fig. 1, leading from a prior dust collector. In Fig. 1, the extension 10 is connected to pipe 12 by a friction fit within the upper end thereof.

Covering the upper end of pipe 10 is a cap 14 having a cylindrical, downwardly extending flange 16 of appreciably greater diameter than that of tube 8. A plurality of holes or apertures 18 are provided at the upper end of tube 8 so that air flowing upwardly through tube 8 may pass laterally through holes or passageways 18, to be directed downwardly by flange 16.

Covering the tube and cap unit just described is an inverted glass jar 20, threaded at its lower end at 22 whereby it may be screwed tightly into a threaded member 24 which is affixed to bottom 6. The engagement of tube 8 with bottom 6 is watertight so that the space 26 between tube 8 and jar 20 is an annular receptacle which may be filled with water to a level in proximity to the lower edge of the flange 16. A rubber washer 25 insures watertight connection between threads 22 and the receiving threaded member 24. It will be appreciated, of course, that jar 20, while made of glass in the preferred form, may be made of metal or any other material capable of holding water. Glass or other transparent material, however, is preferred, as the user is enabled to see at a glance the level of the water therein.

As indicated by the line 28 in Fig. 1, the water level is above the top edge 30 of wall 4 and below the lower edge 32 of flange 16. At level 28, therefore, the surface of the water is clearly visible to the user. When it falls below top edge 30, there is indication that additional water should be added.

Through the top of jar 20 is an aperture 34 through which air passing upwardly through the jar may escape. Preferably the aperture is closed by a screen 36 held in a frame 38 which is secured within the aperture 34. Screen 36 is not, however, relied upon as means for removing dust particles from air leaving the jar, but merely as a protection against the entrance into the jar from the outside of other matter.

The operation of the unit thus far described is as follows: Dust-laden air passes to the unit through the duct to which the unit is connected, as, for example, through pipe 12, passes upwardly through tube 8, out through holes 18, downwardly within flange 16 where it impinges with considerable force on the pool of water contained within jar 20. The impinging action is so vigorous

as to cause the development of a foaming condition as indicated at 40 in Fig. 2. The foam thus produced comprises a multitude of bubbles the aggregate surface area of which adapted to be engaged by the dust particles greatly exceeds the area of the quiet, or even wavy, surface of the water in the jar 20. The dust particles will effectively adhere to the walls of the bubbles in a manner similar to the adherence of fine metallic materials to the walls of the bubbles in the well known "flotation processes" of ore separation and will descend in the water upon rupture of the bubbles along with other particles of sufficient weight to settle by gravity. As a result, dust particles contained within the air will be caught by the water, leaving the air clean as it passes upward in the general direction of arrows 42 and hence out to the atmosphere through screen 36.

The dust trapped in this manner by the water will gradually settle to the bottom of the jar and from time to time may be cleaned out by unscrewing the jar 20 from the threaded member 24.

It will be understood that the level 28 of the liquid must be sufficiently close to lower edge 32 of flange 16 so that there will be sufficient disturbance of the liquid to provide the trapping action. In some cases, where there is an especially strong blower, the water level may be raised to a point above the lower edge of flange 16, so that the air will actually bubble through the water. This, however, is not a preferred arrangement, for in the ordinary case too much back pressure would thereby be imposed on the blower, affecting its efficiency.

In Fig. 4 is shown a modification which may be used under certain pressure conditions. This construction is similar to that shown in Fig. 2 except that a small S-shaped pipe 44 is hooked into one of the holes 18 so that the entering end of the pipe 46 is directly in line with the upward flow of air through tube 8. The lower end 48 of pipe 44 is located below the liquid level. In this manner, a certain proportion of the air that would normally escape through holes 18 is caught by pipe 44 and caused to bubble upwardly through the liquid as indicated at 50. This bubbling action causes a distinct ruffling of the water surface whereby it will be in better condition to catch the dust particles that are blown down thereagainst.

It will be understood that the dimensions of pipe 44 are such that under the air velocity conditions that are present there will be sufficient pressure available within pipe 44 to overcome the head of water that extends from the bottom of the pipe to the water level.

As is well known, the velocity of air flowing from a typical vacuum cleaner is very considerable, and in all cases will be sufficient to cause actual flow of air through pipe 44.

Another modification of the structure is also shown in Fig. 4, in which the lower edge of jar 20, instead of being screwed into corresponding threads, is embedded in any suitable watertight material, illustrated at 52. This watertight material might be in the form of a U-shaped rubber ring into which the lower edge of jar 20 might

be placed, to be sealed thereagainst by cement, indicated at 54. The connection between material 52 and the wall 4 is likewise watertight.

In Fig. 5 is shown a further modification which provides additional means for indicating whether or not the device is actually functioning. Since air is generally invisible, it is in some instances desirable to provide an indicator which will show that the air is flowing in the manner intended. Accordingly, there is mounted on the top of cap 14 a vertical shaft 56 which carries a small propeller 58. Shaft 56 is supported by an easy running bearing 60. Thus, any air flowing upwardly about cap 14 and being expelled through screen 36 will cause the propeller to rotate, thus giving visual indication that the air is flowing through the unit in the manner intended.

As has been explained previously, from time to time the unit must be cleaned of the dirt that has been trapped by the water and which accumulates at the bottom of the container. When the jar 20 is unscrewed from the position shown in Fig. 2, the water and dirt will then be retained within cup 2, from which it may be poured. In the pouring operation, the water tends to run upwardly along tube 8, and in so doing will often times flow to a limited extent through holes 18 to the inside of tube 8. This is objectionable because, when the unit is thereafter righted, the water within tube 8 may drip out on the floor or other surroundings. To prevent this from happening, I have provided a conically shaped flange 62, shown in Fig. 5, which acts to catch any water that may flow upwardly along tube 8. This makes it possible for the user to clean the unit without requiring the exercise of any particular care or skill.

While the invention has been shown in its preferred forms, it will be understood, however, that modifications may be made within the scope of the disclosure without departing from the invention. It is intended that the invention shall not be limited except by the appended claim.

I claim:

45 A unit for removing dust particles from a current of dust-laden air comprising a metal tube for conducting the current of air under pressure having near its upper end lateral apertures, an open receptacle surrounding said tube and extending well above the upper end thereof and containing a liquid to a level a short distance below the apertures in said tube, a cap closing the end of said tube having a downwardly extending peripheral flange narrowly spaced from said tube surrounding said apertures and terminating in such proximity to the surface of the liquid as to cause an annular current of the dust-laden air to impinge thereon with sufficient force to produce a multitude of bubbles presenting a large aggregate surface area to which the dust particles may adhere and from which they will settle into the liquid upon the rupture of the bubbles, and a pipe leading from an aperture in said tube to a substantial distance below the surface of the liquid to supplement the production of bubbles.

PHILIP I. HOLMES.
